UNIVERSAL CONTROL AND TEST DEVICE OR THE LIKE

Richard D. Fullerton, Los Angeles, Calif., assignor to
Pacific Automation Products, Inc., Los Angeles, Calif.,
a corporation of California

Filed Feb. 11, 1960, Ser. No. 59,350

Term of patent 14 years

(Cl. D26—5)

Fig. 1.

Fig. 2.

Fig. 3.

Fig. 1 is a front perspective view of a universal control and test device or the like showing my new design;

Fig. 2 is a side elevational view thereof; and

Fig. 3 is a top plan view thereof.

I claim:

The ornamental design for a universal control and test device or the like, as shown.
